HAT SWEAT BAND

John F. Duerr, Baltimore, Md., assignor to M. S. Levy & Sons, Inc., Baltimore, Md., a corporation of Maryland

Application November 28, 1934, Serial No. 755,205

10 Claims.

(Cl. 2—183)

The present invention relates to new and useful improvements in headwear and more particularly to improved sweat bands for hats, caps or other head coverings of felt, straw or any other material.

An object of the present invention is to provide, in a hat or the like, a sweat band which presents a substantially continuous contact surface to the head of the wearer and wherein elastic means are provided for permitting the band to expand.

A further object of the invention is to provide, in a hat or the like, a leather sweat band having incorporated therewith a yielding insert which remains out of contact with the head of the wearer so that the sweat band leather presents a substantially continuous contact surface to the head of the wearer, said yielding member permitting expansion of the sweat band in order to accommodate variations and irregularities in head sizes, thus insuring a proper fit.

A further object of the invention is to provide, in a hat or the like, a sweat band having the ends thereof joined by an elastic insert in a manner to present a substantially continuous contact surface to the head of the wearer and at the same time permit the sweat band to expand in order to accommodate variations and irregularities in head sizes, thus insuring a proper fit.

The foregoing and other objects of the invention will in part be obvious and will be hereinafter more fully pointed out.

In the accompanying drawing:

Figure 1 is a perspective view of the bottom face of a hat with the sweat band embodying one form of the invention turned outwardly for illustrative purposes.

Figure 2 is a fragmentary side elevation of the sweat band shown in Fig. 1, showing the band slightly expanded.

Figure 3 is a sectional view taken along the line 3—3 of Fig. 2.

Figure 4 is a fragmentary side elevation of another form of sweat band.

Figure 5 is a sectional view taken along the line 5—5 of Fig. 4.

The invention relates generally to a sweat band for a hat, cap or other head covering. The sweat band may be made of leather, cloth or other suitable material and may consist of one or more pieces joined together. In one form of the invention, the sweat band is provided on opposite sides thereof with diagonal slits. These slits may be disposed intermediate the edges of the sweat band or they may extend out to the free edge thereof. Across the back of the sweat band in

the region of the slits, that is, out of contact with the head of the wearer, is glued or otherwise secured a stretchable member which may be of rubber, elastic webbing, or other suitable material. This elastic member permits the sweat band to expand slightly between the diagonal slits. In another form of the invention, one end of the sweat band is interfitted in overlapping relationship with the adjacent end and a strip of rubber, elastic webbing or the like is suitably secured across the back thereof to permit the sweat band to expand without the elastic material contacting with the head of the wearer. This means of permitting the sweat band to slightly expand is advantageous in that it permits a hat of one size to accommodate variations and irregularities in head sizes and, at the same time, provides a cushion for the head of the wearer. Furthermore, the sweat band is similar to the ordinary band in appearance.

Referring more in detail to the accompanying drawing, and particularly to Figs. 1, 2 and 3, the invention is shown as applied to a straw hat 10 having a body portion 11 and a rim portion 12. It is to be understood, however, that the particular type of hat forms no part of the present invention which may be used with any type of head covering, whether of felt, straw or other material. A sweat band 13 is secured around the head opening by stitching 14 or the like. The sweat band 13 is illustrated as being of a single piece of leather joined at the ends by stitching 15, but it is to be understood that the band may be made of a plurality of pieces of any suitable material.

The sweat band 13 is provided at opposite sides thereof with a plurality of slits 16 which are shown for purposes of illustration as extending downwardly from the free edge of the sweat band and which converge diagonally toward one another. There is also provided a central slit 17 which extends inwardly from the free edge of the sweat band at right angles thereto. These slits are normally closed, as shown in Fig. 1, and a strip of rubber 18 is secured by glue or other suitable means to the back of the sweat band out of contact with the head of the wearer when the sweat band is in proper position for the hat to be used. As stated above, the slits are normally closed but if the hat does not exactly fit the head of the wearer, the band may be expanded slightly by a slight spreading or separation of the slits, as shown in Figs. 2 and 3, so that a proper and uniform fit is assured and a cushioning effect is afforded so that the hat will fit much more comfortably. The slight separation of the band at

the slits at the edge of the band will not permit the rubber 18 to contact with the head of the wearer so that a substantially continuous surface is provided by the sweat band material at the 5 point of contact with the head of the wearer, that is adjacent the stitching 14. Webbing or other suitable elastic material may be used in place of the rubber insert, if desired.

A modified form of the invention is illustrated 10 in Figs. 4 and 5. In this form, the ends of the sweat band are joined together in a manner to permit a slight expansion of the same. This sweat band 19 is secured in any suitable manner to the hat body as by stitching 14a, and consists 15 of two pieces 19a, 19b of leather or other suitable material. The ends of the pieces 19a, 19b are joined on opposite sides of the hat in the manner to be immediately described. The edge of the piece 19b is provided with a plurality of tongues 20, 20b. The edge of the piece 19a is provided with a plurality of vertical slits 21 which form openings spaced apart by sweat band material of substantially the width of one of the tongues 20. The tongues 20 fit under the edge of the piece 25 19a and the tongues 20b fit over the edge of the piece 19a and then pass through the slits 21 so that an overlapping fit between adjacent ends of the pieces 19a, 19b is thus afforded. A strip 22 of rubber, webbing or other elastic material is then 30 glued or otherwise suitably secured to the inner or back face of the sweat band over the ends of the tongues 20, 20b. Thus, when the hat is placed on the head of a wearer, the sweat band 19 may expand slightly by a slight separation of the adjacent edges of the pieces 19a, 19b, but the elastic insert will not come in contact with the head of the wearer due to the overlapping arrangement of the ends of the pieces 19a, 19b.

It is to be clearly understood that minor 40 changes in the details of construction and arrangement of parts may be made without departing from the scope of the invention as set forth in the appended claims.

Having thus described the invention, what I 45 claim as new and desire to secure by Letters Patent is:

1. In a hat, a sweat band having one edge secured thereto and being provided with a plurality of slits extending downwardly from the free edge 50 thereof, and a stretchable member secured to the back of said sweat band across said slits whereby to hold said slits normally closed but to permit expansion of said sweat band to accommodate variations and irregularities in head sizes.

2. In a hat, a sweat band having one edge secured thereto and being provided with a plurality of slits extending downwardly from the free edge thereof and terminating short of the secured edge thereof, and a strip of rubber secured to the back 60 of said sweat band across said slits whereby to hold said slits normally closed but to permit expansion of said sweat band to accommodate variations and irregularities in head sizes.

3. In a hat, a sweat band having one edge secured thereto and being provided with a plurality of separate diagonal slits extending downwardly from the free edge thereof in a converging direction but terminating short of the converging point, and an elastic member secured to the back 70 of said sweat band across said slits whereby to hold said slits normally closed but to permit expansion of said sweat band to accommodate variations and irregularities in head sizes.

4. In a hat, a sweat band secured thereto and 75 having adjacent edges in overlapping relation-

ship whereby to present a continuous surface contacting with the head of the wearer, and a stretchable member secured to the back of said sweat band across the overlapping edges thereof whereby to permit expansion of the band while 5 maintaining the continuous contact surface presented to the head of the wearer.

5. In a hat, a sweat band consisting of a plurality of strips of material having adjacent edges fitted together in overlapping relationship where- 10 by to present a continuous surface of material contacting with the head of the wearer, and a strip of elastic material secured to the back of said sweat band over each of the adjacent edges 15 whereby to permit expansion of said sweat band to accommodate variations and irregularities in head sizes.

6. In a hat, a sweat band consisting of a plurality of strips of material secured to the hat body, one edge of each strip being provided with 20 a plurality of tongues, the adjacent edge of another strip being provided with a plurality of spaced slits, alternate tongues of one strip extending under the adjacent edge of another strip and the intermediate tongues extending over the 25 adjacent edge of the other strip and through said slits whereby to present a continuous surface contacting with the head of the wearer, and an elastic member secured to the back of one strip and to the ends of the tongues on the adjacent strip 30 whereby to permit expansion of said sweat band to accommodate variations and irregularities in head sizes.

7. In a hat, a sweat band secured thereto and presenting a substantially continuous surface 35 contacting with the head of the wearer, one end of said sweat band being provided with tongues extending under the adjacent end, and an elastic member secured to the back of said band and connecting said tongues with the adjacent end 40 of said band whereby to permit expansion of the band.

8. In a hat, a non-elastic sweat band having the lower edge thereof secured to the hat body and presenting a continuous surface of material 45 around the said lower edge, the material of said sweat band being divided above the securing line, and means including an elastic member secured to the rear face of said sweat band across the divided area for permitting expansion of said sweat 50 band to accommodate variations and irregularities in head sizes.

9. In a hat, a non-elastic sweat band having the lower edge thereof extending entirely around the hat body and secured thereto by a continuous 55 line of stitching whereby to present a continuous contacting surface, the material of said sweat band being divided above the line of stitching, and elastic means secured to the rear face of said sweat band across the divided area for permitting expansion thereof to accommodate variations and irregularities in head sizes.

10. In a hat, a non-elastic sweat band having the lower edge thereof extending entirely around the hat body and secured thereto by a continuous 65 line of stitching whereby to present a continuous contacting surface, means for dividing the material of said sweat band above the line of stitching and at the free edge thereof whereby to permit maximum expansion at the free edge of said 70 sweat band, and elastic means secured to the rear face of said sweat band across the divided area for permitting expansion thereof to accommodate variations and irregularities in head sizes.
